UNITED STATES PATENT OFFICE.

ANDREW PLECHER, OF LAS ANIMAS, COLORADO.

INDUCTION-COIL.

1,091,589.

Specification of Letters Patent.

Patented Mar. 31, 1914.

Application filed March 16, 1912. Serial No. 684,299.

To all whom it may concern:

Be it known that I, ANDREW PLECHER, a citizen of the United States, residing at Las Animas, in the county of Bent and State of Colorado, have invented a new and useful Induction-Coil, of which the following is a specification.

This invention has reference to improvements in induction coils, and its object is 10 to provide a coil wherein the intensity of the secondary or induced currents is increased, and, also, wherein the windings, both primary and secondary, may be connected in series or in multiple as desired, 15 thus greatly increasing the capacity of the coil over that of an induction coil as ordinarily constructed without any increase in the size of the coil.

The invention comprises an induction coil 20 wherein there is a plurality of both primary and secondary windings with an intermediate magnetic core, while the latter when also in the form of a winding may be employed as a secondary winding.

25 The invention will be best understood from a consideration of the following detailed description, taken in connection with the accompanying drawing forming a part of this specification, with the further understanding that while the structure which is 30 diagrammatically represented in the drawings is capable of practical embodiment similar to the showing of the drawings, the invention is by no means confined to any exact conformity with the illustration of the drawings but may be variously changed and modified so long as such changes or modifications mark no material departure from the salient features of the invention.

40 In the drawings: Figure 1 is a longitudinal diametric section through an induction coil embodying features of the present invention. Fig. 2 is a fragmentary longitudinal diametric section of a portion of a coil 45 of modified construction from that shown in Fig. 1.

Referring to the drawings, there is shown a spool 1 which for lightness of construction, 50 may have an axial passage 2 therethrough, although the presence or absence of the passage has no bearing upon the electrical side of the invention. The spool 1 is usually formed of suitable insulating material.

In the form of the invention shown in the 55 drawings there is first produced upon the spool 1 a winding 3 constituting a second-

ary winding, and assuming that the induction coil is of the step-up type, the winding 3 is made of appropriately fine wire. Upon the winding 3 and suitably insulated therefrom there is produced another winding 4 which in the particular form of the invention shown in the drawings constitutes a primary winding, and assuming that the induction coil is of the step-up order, this 60 winding 4 is made of appropriately coarse wire, the wires of both windings being suitably insulated to prevent short circuits.

Produced upon the winding 4, and, of course, suitably insulated therefrom, is an 65 annular core 5 conveniently made in the form of a winding of iron wire, although in some instances the core may be otherwise constructed. Produced upon the core 5 exterior thereto is another winding 6 like the 70 winding 4, and upon the winding 6 is another winding 7 which may constitute a secondary winding and be similar to the winding 3, it being understood that all the windings are suitably electrically insulated both 75 as to their individual turns and as to each winding as a whole.

Under some circumstances it may be desirable to utilize the core 5 not only as a magnetic core, but as a winding from which 80 current may be obtained, and in such instance the winding 5 may be in the form of a winding of insulated iron wires indicated at 5^a in Fig. 2, while the other windings shown in Fig. 2 may be the same as those of Fig. 1. 90

Suitable leads are, of course, provided for all the windings and assuming that the windings 4 and 6 are primary windings, then these two windings may be coupled up either in series or multiple with a source of electric current which may be a source of alternating current or a source of pulsating current such as is produced by a suitable rheotome as is customarily provided for induction coils where direct current is available. The coils 3 and 7 may be connected up 100 in series or multiple in accordance with the desired intensity of the current to be utilized.

When the induction coil is used as a step-up transformer, the windings 4 and 6 are connected up to the source of current, and, therefore, become primary windings with the windings 3 and 7 acting as secondary windings, and when the induction coil is 110 used as a step-down transformer then the connections are reversed.

It will be understood, of course, that the several windings are properly balanced in accordance with the purpose of the induction coil and when the core is utilized as a winding for delivering current, then such core winding is properly balanced with the rest of the coil. Since the primary windings, considering the windings 4 and 6 as such, are lodged on opposite sides of the core, these windings may be of less radial extent than the single primary winding inclosing a central core, and also the secondary windings are brought closer to the core not only with relation to those turns which are ordinarily nearest the core, but with relation to the turns most remote from the core, wherefore there is a marked increase in the magnetic effect upon the secondary windings over and above the effect produced upon the secondary winding of an induction coil having but a single primary winding about a core, and a single secondary winding exterior to the primary winding.

The several windings may follow the usual practice as regards the gage of the wire employed, the primary and secondary windings being customarily made of copper wire and the core is made of soft iron wire, the specific resistance of which is, of course, higher than that of copper, and when this core is used as a secondary winding a suitable amount of wire is employed not only for the magnetic effect, but to balance with the other secondary windings. The core even though in the form of a winding is the same in effect as the usual bundle of soft iron wires or the laminated cores employed in ordinary induction coils and produces on each primary the full magnetic effect. Also when the core is employed as a secondary winding it not only receives the full induction effect from the primary windings, but reacts magnetically upon the primary windings.

It is customary to wind induction coils circular in cross section, but this does not preclude the winding of the coil of the present invention in other forms, although ordinarily the circular or cylindrical form is the more easily produced, and for this reason alone is usually preferred.

What is claimed is:—

1. An induction coil comprising a core or support of non-magnetic material, a secondary winding produced thereupon, a primary winding on the secondary winding, a layer of magnetic material upon the primary winding, another primary winding upon the magnetic material, and a secondary winding upon the second-named primary winding, the said secondary windings con-

stituting the inner and outer windings of the coil.

2. An induction coil comprising a tubular member of magnetic material, a primary winding produced both outside and inside said tubular member in concentric relation and adjacent thereto, and a secondary winding produced both inside and outside the primary winding with respect to and concentric with the tubular member, said second windings constituting the inner and outer windings of the coil. 65 70

3. An induction coil composed of a plurality of both primary and secondary windings arranged with two primary windings adjacent to each other and two secondary windings separated from each other by the primary windings and constituting the first and last windings of the coil, and a core of 80 magnetic material interposed between the primary windings and constituting the sole magnetic material of the core. 75 85

4. An induction coil composed of two primary windings adjacent to each other and two secondary windings separated from each other by the primary windings, and a core of magnetic material interposed between the primary windings and constituting the sole magnetic material of the core, said magnetic material being in the form of a coil of iron wire constituting a secondary winding in inductive relation to the primary winding and the secondary windings constituting the first and last windings of the coil. 90 95

5. An induction coil comprising a cylindrical core of magnetic material, a primary winding on opposite sides of the core, and a secondary winding on opposite sides of the primary winding and remote from the core, 100 these parts of the secondary winding on opposite sides of the primary winding being balanced as to resistance.

6. An induction coil comprising a non-magnetic insulating support and windings thereon comprising a secondary winding, a primary winding, a magnetic core, a primary winding and a secondary winding in the order and solely to the extent named. 105

7. An induction coil comprising a secondary winding, a primary winding, a magnetic member, a primary winding, and a secondary winding in the order named and constituting the sole electrical and magnetic elements of the coil. 110 115

In testimony that I claim the foregoing as my own, I have hereto affixed my signature in the presence of two witnesses.

ANDREW PLECHER.
